Primary Examiner — Jack Reickel*Assistant Examiner* — Bobby W Jones, II(74) *Attorney, Agent, or Firm* — Knobbe Martens Olson & Bear LLP**CLAIM**

I claim the ornamental design for roof vent with a circular integrated fan, as shown and described.

DESCRIPTION

FIG. 1 is a top perspective view of a roof vent with a circular integrated fan, including an upper and a lower screen; FIG. 2 is a bottom perspective view of the vent of FIG. 1; FIG. 3 is a top view of the vent of FIG. 1; FIG. 4 is a bottom view of the vent of FIG. 1; FIG. 5 is a right side view of the vent of FIG. 1; FIG. 6 is a left side view of the vent of FIG. 1; FIG. 7 is a front view of the vent of FIG. 1; FIG. 8 is a rear view of the vent of FIG. 1; FIG. 9 is a top view of another embodiment of the vent of FIG. 1, with the only difference being the lack of the upper screen; and, FIG. 10 is a bottom view of another embodiment of the vent of FIG. 1, with the only difference being the lack of the lower screen.
